APPARATUS FOR LUBRICATING PNEUMATIC DRILLS

1,114,641.

Specification of Letters Patent.

Patented Oct. 20, 1914.

Application filed October 19, 1912. Serial No. 726,587.

To all whom it may concern:

Be it known that we, VINCENT J. O'BRIEN and GEORGE A. OLIVER, citizens of the United States, residing in the city and county of Denver and State of Colorado, have invented certain new and useful Improvements in Apparatus for Lubricating Pneumatic Drills; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to improvements in means for oiling the hammer barrel and stoping bar cylinder of a pneumatic drill.

It is adapted to be applied particularly to a drill of the nature shown in United States Patent No. 962,717, issued to Vincent J. O'Brien June 28, 1910.

Our invention constitutes means adapted to be operated by the throttle valve of the drill for utilizing pneumatic pressure to force the desired amount of oil into the working parts of the drill.

One object of our invention is to provide means in connection with the throttle such that whenever the latter is moved to admit air to the hammer barrel a charge of oil will be delivered into the hammer barrel. This makes the oiling of the barrel automatic, and guards against injury to the working parts due to the carelessness of the operator in not supplying sufficient oil.

Our invention also provided means for the automatic oiling of the feed bar cylinder when the air is first turned on from the supply hose.

Another object of our invention is to place the contents of the oil cup under pressure whereby each charge of oil is positively forced to the desired point.

One embodiment of our invention is illustrated in the accompanying drawing, in which:

Figure 1 is a view partly in section looking in the direction of the throttle valve handle. The section is taken approximately on the line 1-1, Fig. 2, looking in the direction of the arrow, but for the sake of clearness shows also in full lines the oil passage which

extends entirely through the valve piece and along its opposite sides. Fig. 2 is a view partly in section taken upon the line 2-2, Fig. 1, and looking in the direction of the arrow.

The same reference characters refer to the same parts in each of the views.

In the drawing we have illustrated only that portion of the drill which is directly connected with the oiling apparatus constituting our invention, the reference numeral 5 indicating the hammer barrel, while the feed bar is indicated at 7, the feed bar piston at 8, and the feed bar cylinder at 9. A packing 10 is mounted in the feed bar piston 8 in order to prevent the leakage of air. A head-block 11 is interposed between the hammer barrel 5, and the feed bar cylinder 9, this head-block being threaded at 12 to receive the threads of an air-supply pipe (not shown). Communicating with the space surrounded by these threads 12 is a conical valve seat 13 in which is rotatably mounted a valve piece 14 having a cylindrical exposed portion 15 perforated at 16 to receive a pin 17 for fixing to the valve piece a handle 18. A slot 19 is cut into the inner portion of the handle 18 extending partially around the circumference thereof, and a pin 20 fixed in the head-block 11 acts as a stop against the ends of the slot 19 to limit the rotative action of the valve piece.

The head-block 11 has a portion 21 extending laterally, having a comparatively large bore 22 therein, this bore being threaded at 23 to receive the threaded lower portion 24 of an oil cup 25. A threaded plug 26 is provided to close the top of the oil cup 25 and to act as a plunger to force the oil downwardly. Within the cup 25 is a tube 27 fixed by any suitable means in the lower portion 24 of the cup and terminating at its upper extremity just below the position of the plug 26 when screwed down to its lowest position. Communicating with the bottom of this tube 27 is a duct 28 which leads downwardly into a comparatively short duct 29 in communication with an annular passage 30. The lower portion 24 of the oil cup has one other duct 31 connecting the cup 25 with a bore 22 in the head-block. A duct 32 leads from the valve seat into the hammer barrel, but is closed from the latter by means of a plug

33. A passage 34 connects this duct 32 with the annular passage 30 in the lower portion 24 of the oil cup, and a passage 35 connects the bore 22 to the valve seat. The passages 34 and 35 are in the same plane.
- 5 In the larger end of the valve piece we provide a chamber 36 which is always in communication with the air supply, provided the latter is turned on. When the 10 valve piece is in the position shown in the drawing, the chamber 36 is in communication with the duct 32 by means of a duct 37, as is clearly shown in Fig. 2. A short duct 38 connects this chamber 36 with the passage 39 when the valve piece is slightly turned 15 from the position illustrated in the drawing. Extending entirely through the valve piece is a duct 40 connected at one end to a short passage 41 formed along the side of the 20 valve piece 14. At its opposite end the duct 40 is connected to a passage 42 also formed in the side of the valve piece, this latter passage being angular and having a portion extending away from the handle of the valve 25 piece and another portion extending toward the handle and ending in an enlarged part 43 which, in the position of the valve piece illustrated, is directly opposite the passage 35 leading from the bore 22.
- 30 In the head-block there is a large passage 44 connecting the valve seat with the hammer barrel, through which the hammer barrel receives its air supply when the valve piece is rotated to cause the opening 45 therein to register with the passage 44. Another large passage 46 extends through the 35 head-block in a direction parallel with the passage 44 by means of which the pressure within the hammer barrel and feed bar cylinder is equalized when the opening 47 extending entirely through the valve piece is caused to register with the passage 46. This 40 condition is simultaneous with the registering of the opening 45 and the passage 44.
- 45 Although the construction and operation of the drill as a whole do not enter into this application, it may be well to state that means are provided for equalizing the pressure in the hammer barrel and feed bar cylinder in order that the drill may be held up to the work with just the proper amount of 50 pressure.
- 55 The operation of our improved oiling device is as follows: It should be understood that when the drill is adjusted to the working position, the stop-cock in the air supply (not shown) is cut off. It being assumed that the oil cup 25 is properly filled, the screw plug 26 is turned downwardly to force 60 oil through the tube 27, passages 28, 34, 32 and 37, into the chamber 36, and through the passage 31 into the bore 22, and through the passage 35 into the enlarged portion 43 of the passage 42 and thence through said passage 65 into the duct 40 extending through the valve piece, the valve piece being understood to be in the position illustrated in the drawing, which is the position that it will occupy when the air supply is turned off from communication with the hammer barrel. There being now a charge of oil within the chamber 36, the stop-cock in the air supply hose (not shown), is opened, whereby pressure is communicated through the passages 37, 32, 34 and 28 and the tube 27 to the 70 surface of the oil in the oil cup 25, thus positively forcing oil through the passage 31 in the lower portion of the oil cup, the bore 22 and the passages 35, 43 and 42 into the duct 40 in the valve piece. The handle 18 of the valve piece is now turned slightly to cause the duct 38 to register with the passage 39, whereupon the air pressure in the chamber 36 will force the oil therein into the feed bar cylinder 9. Continuing the rotation of the handle 18 in the same direction, the passages 41 and 42 in the valve piece will be brought into register with the large passage 46 through the head-block, and the oil contained in these passages and in the duct 40 will be forced into the hammer barrel 5 due to the fact that the pressure in the hammer barrel up to this time is atmospheric, while that in the feed bar cylinder is greater 10 than atmospheric pressure, on account of its preceding connection to the air supply through the duct 38 and the passage 39. A still further rotation of the handle 18 will bring the openings 45 and 47 into register 15 with the passages 44 and 46 respectively, whereupon the drill is set in motion.
- 50 Although we have described the motions of the valve piece whereby the different ducts and passages are brought into register separately, it should be understood that in practice this movement of the valve piece may be practically continuous. If at any time the operator should desire to send an additional charge of oil into the hammer barrel, it is necessary for him to merely 110 turn the throttle off and on again.
- 55 We claim:
1. In combination with a head-block having a valve seat therein and a passage therethrough intercepted by said valve seat, a valve piece having a passage therethrough adapted to join the intercepted portions of said passage through the head-block when the valve piece is in one position, said valve piece having a second passage adapted to 115 connect the intercepted portions of said passage through the head-block when said valve piece is in a second position, and means for supplying said second passage with a charge of oil.
2. In apparatus of the class described, an air supply pipe, a hollow closed element, a head block mounted adjacent said element, said head-block containing a valve seat, a rotatable valve piece mounted in said seat 120
- 125
- 130

and having a chamber arranged to be normally in communication with the air supply pipe, an oil cup mounted upon said head-block, the latter having two passages connecting the oil cup and valve seat, said valve piece having two ducts, one of which connects one of said passages with the chamber when the valve piece is in one position and the other of which passes entirely through the valve piece and is in communication with the other of said passages when the valve piece is in the same position, a passage in the head-block connecting the valve seat and hollow element, a duct in said valve piece connecting the last named passage with the said chamber when the valve piece is in a position at a slight angle to the first named position, said block having a passage therethrough connecting the hollow element with the opposite side of the block and intercepted by the valve seat said duct passing entirely through the valve piece being adapted to be brought into line with the last named passage in the head-block.

25 3. In combination, a head block, a throttle valve mounted therein and arranged to control the passage of air from said valve in opposite directions through said block and means adapted to be controlled by the operation of said valve for forcing oil through said block in both of the aforesaid directions.

4. In combination, a head block, a throttle valve mounted therein and arranged to control the passage of air from said valve in opposite directions through said block and means adapted to be controlled by the operation of said valve for forcing oil through said block first in one of the aforesaid directions and then in the other.

40 5. In combination with a block, a throttle valve mounted therein and arranged to control the passage of air from said valve in opposite directions through said block, an oil cup mounted upon the block, said valve being adapted to control admission of air to said cup and the passage of oil from said cup through said block to said valve and

thence through said block in the aforesaid opposite directions.

6. In combination, a head block, a hollow closed element mounted upon one side of said block, a throttle valve mounted within said block, said valve having an oil chamber and an oil passage, means for forcing oil into said chamber and passage and means controlled by said valve for forcing oil under pressure from said chamber to the hollow element and for utilizing the pressure in the latter to force the oil out of said passage through the block to the side opposite the hollow element.

7. In combination, a head block, a hollow closed element mounted upon one side of said block, a throttle valve mounted within said block, said valve having an oil passage therethrough, means for forcing oil into said passage and means controlled by the valve for admitting air under pressure to said hollow element and then utilizing the pressure in said hollow element to force the oil in said passage through the block to the side opposite the hollow element.

8. In combination, a head block provided with an air passage therethrough, and with a valve seat intercepting said passage, a rotatable valve piece mounted in said seat, said valve piece having an air passage therethrough adapted to align with the first named passage, said valve piece having also a comparatively small oil passage therethrough to one side of the air passage and at an angle therewith, the ends of said oil passage extending into the zone of the air passage whereby, when the valve piece is at the proper angle, the portions of the air passage in the block are joined by the said oil passage.

In testimony whereof we affix our signatures in presence of two witnesses.
